UNITED STATES PATENT OFFICE

ROBERT M. HYDE, OF LAUREL, MISSISSIPPI; VESTA M. HYDE ADMINISTRATRIX OF
SAID ROBERT M. HYDE, DECEASED

SANITARY CLOSET

Application filed January 16, 1931. Serial No. 509,238.

The present invention relates to improvements in toilets and the primary object of the invention is to provide a sanitary odorless dry toilet primarily intended for use with tank or pit closets.

A further object of the invention is to provide a sanitary dry closet embodying means automatically operable for preventing the emission of odors into the toilet room.

10 A further object of the invention is to provide a closet provided with trap plates operable by the seat to be automatically opened when a weight is brought upon the seat and automatically closed when the weight is removed.

15 A further object resides in the arrangement whereby the closet will be properly vented at all times, and the arrangement whereby the trap plates will be disposed in a substantially protected position within the bowl or hopper when in use.

20 Other objects and advantages of the present invention will be apparent from the following detailed description taken in connection with the accompanying drawings forming a part of this specification and in which drawings:

25 Figure 1 is a top plan view of the sanitary closet and showing the seat in a lowered position.

Figure 2 is a section on the line 2—2 of Figure 1 but showing the seat in a raised position and the trap plates closed.

30 Figure 3 is a rear plan view of the closet with the seat closed.

Figure 4 is a vertical section on the line 4—4 of Figure 3.

35 In the drawings and wherein similar reference characters designate corresponding parts thruout the several views, the improved closet comprises a bowl or hopper A provided with the seat B, and C designates closure means operable by movement of the seat B for automatically opening and closing passage thru the bowl or hopper A.

The bowl A is preferably though not essentially made of metal and embodies a rectangular shaped base 5 including vertical front and rear walls 6 and 7 respectively and vertical side walls 8. Extended about the lower

edges of the base walls is an outturned flange 9 for resting upon a suitable floor 10 about the margins of an opening 11. Removably fitting upon the upper end of the base 5 is a cap or head piece 12 including an upright cylindrical body portion 13 provided at its lower end with a rest flange 14 for seating upon the upper edge of the base 5. This rest flange 14 is provided about its marginal edges with a downturned retaining flange 15 which snugly engages about the upper edges of the base walls 6, 7 and 8 to prevent side movement of the head piece and also form a tight joint between the head piece and base to prevent escape of odors at the joint. As will be seen the diameter of the cylindrical body portion 13 is less than the size of the base 5 so that the rest flange 14 forms an inwardly extending shoulder along the upper edge of each wall of the base.

The seat B is of ordinary circular shape and is hingedly connected at its rear portion to the rear side of the cylindrical body portion 13. Secured to the under side of the seat B is a hinge member 16 which is pivotally connected to a bracket 17 carried by the body portion 13. The hinge member 16 is provided with a rearwardly extending arm 18 which extends rearwardly of the pivotal axis of the seat and has attached to its rear end, the upper end of a coil spring 19. The lower end of the spring 19 is attached in any suitable manner to the base flange 9 and this spring serves to normally raise the seat B to a vertical position from above the bowl as shown in Figure 2.

40 Referring now to the closure means C for opening and closing passage thru the bowl A upon movement of the seat B, the same includes a co-acting pair of swinging trap plates 20—20 of rectangular shape and each having a tubular rolled edge 21. These plates 20 which are preferably of sheet metal, are of a length from front to back, greater than the diameter of the cylindrical body portion 13 and of a width slightly greater than one half the width of the base 5 whereby the free edges of the plates will overlap when the plates are in their normal closed position as shown in Figure 2. Extended thru the tubular edge 100

21 of each trap plate 20 is a hinge pin 22 the ends of which extend beyond the ends of the plates and have pivotal mounting in the upper portions of the base walls 6 and 7 closely adjacent the base side walls 8. The retaining flange 15 may be provided with downwardly opening slots as shown in Figure 3 to accommodate the ends of the pins 22. The hinge pins 22 are fixed in the tubes 21 whereby upon 10 rotation of the pins, the trap plates will be moved therewith. The rear projecting end of each hinge pin 22 is formed with a crank arm 23 provided at its end with an eye 24 in which are hingedly connected the lower ends of links 25 which may be formed with eyes 26 for connection with the eyes 24. Extended transversely thru the arm 18 rearwardly of its pivot, is a rod 28 having an eye 29 formed at each end thereof for connection 20 in the eyes 30 formed at the upper end of each link 25.

When the seat B is in its normal raised position as in Figure 2, the crank arms 23 are inclined outwardly and downwardly at an 25 angle of about 45° from the side walls of the base, and when the seat is lowered upon the upper edge of the cylindrical body portion 13, the crank arms are swung upwardly thru substantially 90° so as to extend outwardly 30 and upwardly from the base side walls as in Figure 3.

In operation, the seat B is normally swung to a vertical position by the spring 19 which causes a downward pull on the rear end of 35 the arm 18. Downward swinging of the arm 18 depresses the links 25 causing the crank arms 23 to move downwardly and the hinge pins 22 rotated thru 90° thus swinging their respective trap plates 20 upwardly against the under side of the rest flange 14. This 40 upward swinging of the trap plates 20 forms a closure between the bowl sections 5 and 12 and prevents the emission of odors. When the seat B is swung downwardly for use, the 45 links 25 exert an upward pull upon the crank arms 23 whereby the trap plates 20 swing downwardly against the base side walls 8 to a position beneath the shoulder formed by the 50 rest flange 14.

Opening thru the upper portion of the rear base wall 7 is a vent pipe 35 for venting of odors entrapped in the base 5 beneath the trap plates 20.

Thus it will be seen that an improved 55 sanitary dry toilet has been provided which will effectively overcome the many objectional features of this type of toilet now in general use and wherein no means is provided to prevent the emission of odors into the toilet room. 60 It will also be apparent that a simple construction has been provided whereby the device may be economically constructed, and one which will be automatic in its operation for accomplishing the object in view.

65 Changes in detail may be made to the form

of invention herein shown and described, without departing from the spirit of the invention or the scope of the following claims.

I claim:

1. In a closet of the class described, a bowl comprising a rectangular base portion and a top portion including a cylindrical body portion providing an internal downwardly facing shoulder about the upper end of the base portion, a seat hinged to rest upon the upper edge of said top portion, a flat trap plate hingedly mounted along one edge beneath the shoulder at each of the side walls of the base portion, means operatively connected between the seat and said plates for closing the plates across the bowl when the seat is raised and opening the plates against the side walls of the base when the seat is lowered, and spring means normally holding the seat in a raised position. 70 75 80

2. In a closet of the class described, a bowl comprising a base portion and a body portion mounted upon the base portion each having a vertical opening therethru, and an internal downwardly facing shoulder at the lower end of the body portion, a seat hinged to rest upon the upper edge of the body portion, means normally retaining the seat in a raised position, a pair of trap plates hinged at one edge in the bowl beneath said shoulder for closing the opening thru the bowl, and means for operating the plates upon raising and lowering of the seat. 90 95 100
